CONVERTIBLE ROCKER AND BED UNIT

Earle E. Lockwood, 35 Crosby St.,
East Hartford, Conn. 06118

Filed Sept. 25, 1967, Ser. No. 8,714

Term of patent 14 years

Int. Cl. D6—01

U.S. CL. D15—11

Fig. 1

Fig. 2

Fig. 3

Fig. 4

Fig. 5

Fig. 6

Fig. 7

FIG. 1 is a perspective view of the convertible rocker and bed unit showing my new design in position for use as a rocker.

FIG. 2 is a side elevation of the convertible rocker and bed unit in its rocker position, the opposite side thereof being a mirror image of the side shown.

FIG. 3 is an end elevation of the convertible rocker and bed unit in its rocker position.

FIG. 4 is a top plan of the convertible rocker and bed unit in its rocker position.

FIG. 5 is a side elevation of the convertible rocker and bed unit in its bed position.

FIG. 6 is a bottom view of the convertible rocker and bed unit in its bed position.

FIG. 7 is an end elevation of the convertible rocker and bed unit in its bed position.

I claim:

The ornamental design for a convertible rocker and bed unit, as shown and described.
